US0D1053651S

(12) **United States Design Patent** (10) **Patent No.:** **US D1,053,651 S**
(45) **Date of Patent:** **** Dec. 10, 2024**

(54) **DISPENSER**

(71) Applicant: **PepsiCo, Inc.**, Purchase, NY (US)

(72) Inventors: **Stephen Lim**, Chappaqua, NY (US);
Christian Stolarz, Brooklyn, NY (US);
Alex L. Gray, Jr., White Plains, NY
(US); **Raymond Estrella**, Elmont, NY
(US)

(73) Assignee: **PepsiCo, Inc.**, Purchase, NY (US)

(**) Term: **15 Years**

(21) Appl. No.: **29/898,351**

(22) Filed: **Jul. 26, 2023**

Assistant Examiner — Darryl J Dardenne

(74) *Attorney, Agent, or Firm* — Sterne, Kessler, Goldstein & Fox P.L.L.C.

(57) **CLAIM**

The ornamental design for a dispenser as shown and described.

DESCRIPTION

FIG. 1 is a top perspective view of a dispenser showing the claimed design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dashed broken lines in the figures show portions of the dispenser that form no part of the claimed design.

The dot-dash broken lines in the figures show boundaries that form no part of the claimed design.

1 Claim, 8 Drawing Sheets
